TOY PISTOL

Robert J. Rickenbacher, Columbus, Ohio, assignor to The Kilgore Mfg. Company, Westerville, Ohio, a corporation of Ohio

Application November 25, 1940, Serial No. 367,035

6 Claims. (Cl. 42—57)

This invention relates to toy pistols for detonating explosive charges, and particularly toy pistols of the repeating type.

One of the difficulties encountered when using toy cap pistols of the repeating type is the tendency of the mechanism of the pistol to refuse to operate after the pistol has fired a number of charges. The explosive charges cause considerable corrosion of the operating mechanism of the top pistols, and in fact there is a tendency toward forming a crust over the working mechanism of the pistol. After a short interval of operation the mechanism of the pistol becomes so corroded as to refuse to operate. This condition is particularly aggravating in connection with the repeating type of toy cap pistol, wherein considerable mechanism is present for firing successive detonating charges and for feeding a cap strip through the pistol.

I have found that if the mechanism of the pistol is suitably lubricated that the aforementioned difficulty is considerably relieved, and in fact may be even eliminated. However, according to the present structures of toy cap pistols available on the market no thought has been given to the problem of lubrication of the working mechanism, unless the pistol is disassembled and a manual oiling or lubrication is given the working parts of the mechanism.

It is thus an object of this invention to provide means by which a toy cap pistol can be automatically lubricated at periodic intervals.

It is another object of the invention to provide a toy pistol which is constructed and arranged for detonating explosive charges carried upon a thin sheet-like body, and which is adapted to receive lubricant from the sheet-like body as it traverses the interior of the pistol.

It is another object of the invention to provide a toy pistol of the aforementioned type wherein a lubricant is scattered within the interior of the pistol upon detonation of an explosive charge.

It is another object of the invention to coordinate the movement of an explosive charge cap strip through a toy pistol with the movement of the concussion hammer in such a manner that the hammer will scatter lubricant within the interior of the pistol upon striking the cap strip.

It is another object of the invention to provide a toy pistol of the aforementioned type wherein the concussion hammer is arranged to strike the lubricant body to scatter a lubricant within the pistol.

It is another object of the invention to pro-

vide a strip of explosive charges which is arranged to carry a lubricant.

It is another object of the invention to provide a cap strip in accordance with the foregoing object wherein the lubricant is carried adjacent one or more of the explosive charges.

It is a further object of the invention to provide a cap strip in accordance with the previously mentioned object wherein the lubricant, positioned adjacent the explosive charges, is adapted to be scattered within the pistol substantially simultaneously with detonation of a charge.

It is another object of the invention to provide a method for lubricating the working parts of a toy cap pistol, wherein the lubricant is carried within the pistol upon a thin sheet-like strip and is scattered within the pistol by means of the concussion hammer.

It is another object of the invention to provide a thin sheet-like body having a plurality of explosive charges arranged at spaced intervals thereon, and having a body of lubricating material adjacent at least some of the charges.

It is another object of the invention to provide a method for making a cap strip for a toy pistol, wherein the strip carries both lubricant and explosive.

It is another object of the invention to provide a method for placing a lubricant upon a cap strip for a toy cap pistol.

Further objects and advantages will be apparent from the description and the drawings.

In the drawings:

Figure 1 is a cross-sectional view of a toy cap pistol of the repeating type wherein the teachings of the invention can be practiced;

Figure 2 is a perspective elevational view of a cap strip for use in the pistol disclosed in Figure 1;

Figure 3 is a cross-sectional view along line 3—3 of Figure 2 showing one method of introducing a lubricant adjacent the explosive material;

Figure 4 is a cross-sectional elevational view of a cap strip showing the manner of positioning a lubricant charge adjacent a powder charge;

Figure 5 is an elevational view of a cap strip showing a lubricant charge encircling a powder charge;

Figure 6 is a perspective elevational view of a cap strip showing continuous lines of lubricant positioned adjacent a succession of powder charges;

Figure 7 is a perspective view of a spiral roll of a strip of explosive charges wherein a single line

of lubricant is applied upon the cap strip and over the explosive charges;

Figure 8 is a perspective cross-sectional view of a device for applying lubricants to helical rolls of cap strips;

Figure 9 is an elevational view of a cap strip showing a lubricant spot positioned adjacent an explosive charge, and in alignment with the continuous line of explosive charges;

Figure 10 is a partial view of a pistol showing the type hammer used for exploding the charges and scattering the lubricant of the cap strip disclosed in Figure 9;

Figure 11 is a perspective view of a cap strip wherein the strip itself has absorbed a lubricant;

Figure 12 is a cross-sectional view taken along line 12-12 of Figure 11 and shows the manner of protecting the explosive charge from the lubricant soaked enclosure strips of Figure 11;

Figure 13 is a perspective view of the cap strip showing the manner of positioning an oil base lubricant above an explosive charge, and the manner of protecting the explosive from absorbing the lubricant;

Figure 14 is a perspective view of a cap strip showing a disk which has absorbed an oil base lubricant, and surrounding a powder charge;

Figure 15 is a perspective view of a cap strip showing the lubricant spot in line with the explosive charges, which spot can be positioned at periodic intervals;

Figure 16 is a partial cross-sectional view of a toy cap pistol showing a manner of carrying the lubricant into the interior of the cap pistol by means of a separate lubricant strip;

Figure 17 is a perspective view of a disk type explosive strip and one means of applying lubricant adjacent the explosive charges.

Figure 18 is a perspective view of a cap strip showing the lubricant on the strip in interrupted lines along the edge of the strip.

In this invention a method and apparatus is provided for lubricating the working parts of a toy pistol which is constructed and arranged for detonating explosive charges. The invention is particularly adaptable for use in connection with the repeating type toy cap pistol wherein considerable mechanism is provided for operating the concussion hammer and for feeding a cap strip through the pistol in a manner to bring successive explosive charges into proper alignment with the concussion hammer.

The toy cap pistols as constructed for sale upon the market are adapted to feed an explosive charge into alignment with the concussion hammer, which is operated by a suitable mechanism connected to the trigger for detonating the charge. The resultant explosion scatters the products of combustion within the interior of the body of the pistol whereby the various operating mechanisms become coated with the products of combustion of the explosive. These products of combustion are extremely corrosive, and as a result, the working mechanism of the pistol soon becomes useless.

It is possible to overcome the detrimental effects of the incrustation upon the operating mechanism if the working elements are sufficiently lubricated. However, it has not been possible to lubricate the working parts of a cap pistol unless the pistol was disassembled and manual lubrication was applied to the various working parts. This invention provides an apparatus for automatically lubricating the working parts of a toy cap pistol.

The invention can be applied to any pistol which is constructed and arranged for detonating charges of an explosive, whether the charges are individual charges or are placed upon a strip in spaced relation for feeding through a repeating type pistol. The method of lubrication can be used in any pistol which has heretofore been manufactured, and thus is not limited to any particular pistol structure.

To illustrate the manner in which the invention can be practiced in connection with toy cap pistols, Figure 1 represents a cross-sectional view through any conventional repeating type cap pistol. The pistol consists of a body 10 having a grip 11. The body 10 is provided with a substantially hollow interior firing chamber 12. A trigger 13 is pivotally mounted at 14, the pivot 14 being exposed to the interior of the chamber 12. The trigger 13 is a bell crank lever which has an extension 15 on the rear end thereof. A trigger operating spring 16 encircles the pivot 14 and has the forward end thereof carried by a pin 17. The rear end of the spring 16 is carried upon the extension 15 provided on the trigger 13. The trigger 13 is provided with a widened portion upon the rear portion of the bell crank, and has an angular face 18 cut thereon which provides a nose 19. The nose 19 is adapted to engage the nose 20 of the hammer 21 when the trigger 13 is pulled rearwardly, thereby cocking the hammer 21 about the pivot 22a. Upon complete rearward movement of the trigger 13, the nose 19, on the trigger 13, will release the nose 20 on the hammer 21 to permit the spring 22 to move the hammer forward in a firing stroke.

A feeding lever 23 is carried upon the trigger 13. This lever 23 is pivotally mounted at 24 and is urged in a forward position against the cap strip 25 by means of the spring 16 which also rests upon a pin 26. When the trigger 13 is pulled rearwardly the feeding lever 23 moves upwardly to advance the cap strip 25. The cap strip 25 is part of a continuously helical roll 30 which carries a plurality of explosive charges spaced at regular intervals.

This cap pistol, as heretofore described, is merely one of a number of structures upon which the principles of this invention can be practiced, the details of structure of the mechanism for the cap pistol varying considerably according to the make and manufacture thereof. As long as the products from an explosive charge can reach the operating mechanism of a toy cap pistol, the need for the principles of this invention is required. As noted by the structure of Figure 1 which is conventional for toy cap pistols, the operating mechanism for tripping the compression hammer and for feeding the cap strip is arranged within the firing chamber 12, and thus can receive the products of combustion from the explosions of the various charges.

In order to lubricate the operating mechanism of such toy cap pistols, this invention places a lubricant upon the cap strip 25 which may be scattered within the firing chamber 12 by means of the hammer 21 striking the lubricant carried by the strip, or by means of the detonation of the explosive charge. The lubricant used can be either of an organic or an inorganic nature, the essential requirement being that it can be scattered upon being struck by the hammer of the pistol or by means of the explosion of a charge. I have found that if lubricant is arranged upon a cap strip either adjacent each of the charges or adjacent periodically spaced

charges that sufficient lubricant can be scattered within the firing chamber 12 that the working elements will receive sufficient lubrication to prevent the deleterious corrosion by the products of combustion of the explosive charge. The inorganic lubricants, such as graphite, zinc stearate, or lamp black, are of a non-oily nature and hence can be handled as dry powders. Lubricants of this type may be mixed with a charge of explosive, or may be positioned adjacent the charge upon the cap strip in small bodies. No particular precaution need be taken as to the manner of their application since they are dry materials and will in no way effect the detonation of the explosive charge. The materials may be placed upon the cap strip either by dusting the materials thereon by some suitable method, or by confining small bodies of the lubricant adjacent certain of the explosive charges.

The organic lubricants which are of an oily nature, require certain precautions to be taken to prevent the oil of the lubricant from being absorbed into the powder charge when the lubricant is placed adjacent the powder charge on the cap strip. Various methods for protecting the powder charge from the oil of the organic lubricants can be provided, some of which will be hereinafter more fully described.

However, the teachings of this invention include the use of a strip containing a lubricant being passed through the pistol mechanism in a manner that the mechanism can receive lubricant from the strip, either directly or indirectly. Such indirect methods of receiving lubricant as scattering lubricant by the explosive charge, or by compression of the hammer upon the lubricant body are both practical methods of scattering sufficient lubricant within the firing chamber of the pistol that the various working parts will receive sufficient lubrication to prevent drying and corrosion of the surfaces thereof. By carrying the lubricant through the pistol in combination with movement of the cap strip through the same, an automatic means is provided for lubricating the working parts of the pistol, whereby the life of the pistol is greatly increased without the necessity of any particular care being taken by the user.

There are various methods by which the lubricant can be carried, either upon or in cooperation with the movement of the cap strip through the pistol.

The inorganic lubricants, such as graphite, lamp black and the others, are particularly adaptable for direct mixing with the explosive charge. Since lubricants of this type are of a non-oily nature there is no danger of any dampness effecting the operation of an explosive charge when struck by the hammer of a pistol.

As indicated in Figures 2 and 3, a succession of explosive charges 31 can be placed upon the cap strip 25 in spaced relation to each other. A small charge of an inorganic lubricant, such as graphite, can be mixed with the powder charge and be enclosed within the paper strip forming the cap strip 25. Such a charge is indicated at 32, see Figure 3. When using a cap strip of the type carrying the lubricant with each explosive charge, the lubricant will be scattered within the firing chamber 12 of the pistol each time a charge is detonated. It may thus be seen that the lubricant carried by the powder charge will offset the detrimental effects of the products of combustion of the charge since the lubricant will be scattered within the firing chamber 12 of the

pistol. The working parts of the pistol mechanism will thus be lubricated since the lubricant will be dispersed throughout the same area as is effected by the products of combustion of the explosive.

As indicated in Figure 4, the lubricant may take the form of a small body of lubricant 33 positioned adjacent the powder charge 31 upon the cap strip 25. These small bodies of lubricant 33 can be placed upon the cap strip 25 at the same time the powder charge 31 is positioned thereon and may be placed adjacent each powder charge, or be placed at intervals along the cap strip 25, depending upon the quantity of lubricant required to obtain the desired degree of lubrication by the parts effected by the products of combustion of the powder charge. The small bodies of lubricant 33 can be an organic or inorganic material depending upon the type of enclosing material used for the cap strip 25. If the oily organic lubricants are used, it is essential that the powder charge be protected from absorbing oil from the lubricant. In which case the cap strip 25 can be made from an oil proof material.

In Figure 5 there is disclosed substantially the same arrangement as disclosed in Figure 4, except that the lubricant body 33a consists of a ring which encloses the powder charge 31. This arrangement can be used if it is found desirable to place a substantial quantity of lubricant upon the cap strip 25 for dispersion within the firing chamber of the pistol.

Figures 6 and 7 disclose a manner of application of lubricants adjacent the powder charges upon a cap strip 25 wherein the lubricant is arranged in a continuous line adjacent the powder charges. In Figure 6 the continuous lines of lubricant are positioned parallel with the edges 40 of the cap strip 25 so that the powder charge 31 is positioned between two parallel lines of lubricant. The lubricant lines 37 may be either continuous along the entire length of the cap strip 25, or the lines may be interrupted in a manner illustrated in Fig. 18 so that the lubricant lines 37a will appear adjacent only one or only several of the powder charges and parallel to the edges of the cap strip 25.

In all of the arrangements heretofore described for positioning lubricants adjacent the powder charges, the powder charges and the lubricant can be placed upon one strip of material for forming the cap strip. A second strip of material, such as indicated at 38, see Figure 6, can 55 enclose the charges of lubricant and powder, thereby holding the materials in their proper position upon the cap strip 25 without permitting loss of either the powder charge or the lubricant.

As disclosed in Figure 7, the continuous line 60 of lubricant 39 can be applied to any previously manufactured strip of powder charges. In this modification the cap strips can be manufactured in the conventional manner wherein the successive charges are enclosed between sheets of material and are subsequently rolled into a helical roll. In this arrangement, before the strips are coiled, the lubricant can be mixed with a suitable binder and applied either along the edges of the cap strip or over the powder charges themselves. 65 It is of course understood that the binder is only required if the lubricant is of a type such as graphite or some other loose powder form of inorganic lubricant. If the lubricant should be of an oily base, such as the organic lubricants, the 70 material from which the cap strip is made will 75

of course be a grease-proof material to prevent absorption of the oil into the explosive charges.

In Figure 9, there is represented a form of a cap strip having individual charges of a lubricant positioned adjacent each of the powder charges. In this form the powder charges 40 are placed upon the cap strip 25 in the conventional manner. The lubricant charges 41 are positioned adjacent each powder charge 40 or can be spaced at regular intervals adjacent the powder charges 40. In the arrangement thus disclosed the powder charge 40 and the lubricant charge 41 are to be struck by the hammer 21a substantially simultaneously. The hammer 21a of the pistol is provided with two concussion heads 42 and 43, the concussion head 43 striking one of the charges while the concussion head 42 strikes the other of the charges upon the cap strip. This arrangement provides means whereby the scattering of the lubricant is not dependent upon the detonation of the explosive charge, the pressure of the stroke of the hammer 21a scattering the lubricant charge. However, since the lubricant charge 41 is adjacent the powder charge 40 the detonation of the powder charge will aid in dispersing the lubricant within the firing chamber of the pistol.

Figures 11 and 12 disclose a method for carrying lubricant within the body of the material forming the cap strip 25. In this arrangement the upper and lower sheets, 45 and 46 respectively, are adapted to absorb an oily lubricant. The powder charge 47 is protected by means of an oil-proof coating 48 when positioned between the lubricant absorbed strips 45 and 46. Such a lubricant absorbed strip can carry lubricant to the working parts of the pistol either by direct contact with the parts or by dispersing the lubricant upon detonation of the explosive charge. Since the cap strip 25 of the form of device disclosed in Figures 11 and 12 carries considerable lubricant of an oil base type, this cap strip can be used particularly advantageously to lubricate by contact, and since the cap strip itself will be at least partially destroyed upon detonation of the explosive charge, it can be seen that the cap strip material engaging the various working parts will carry a lubricant thereto by contact after being dispersed by explosion of the powder charge.

The cap strip 25 of Figure 13 consists of a strip of material 50 upon which the powder charges are placed in spaced relation. An oil-proof strip of material 51 is placed over the powder charges 52 so that a grease or oil spot 53 can be positioned upon the oil-proof paper 51 adjacent the powder charges 52. A cover strip 54 is then placed over the grease or oil charges 53. This arrangement provides another method for protecting the powder charges 52 from any deleterious effect from the oil within the grease charges 53.

Figure 14 discloses the positioning of an oil soaked disk 55 encircling a powder charge 56, while Figure 15 discloses an oil or grease spot 57 positioned in alignment with the powder charges 58, and being adapted to be positioned at periodic intervals along the cap strip 25. It is of course understood that the oil soaked disk 55 or that the oil spot 57 could just as well be inorganic or non-oily lubricants, such as graphite.

Figure 17 discloses a cap strip 60 in the form of a disk having a plurality of charges 61 equally spaced about a circle on the disk. A cooperating disk 62 is adapted to be positioned adjacent the surface of the disk 60, and carries a lubricant, 75

either by absorption within the disk 62 or by placement upon the surface of the disk.

In the various forms of cap strips heretofore described it can readily be seen that the lubricant is arranged in a manner to be scattered within the fire chamber of the pistol by explosion of the powder charge. Some of the forms provide means for scattering the lubricant directly within the fire chamber by means of compression of the hammer of the pistol upon the cap strip, or upon the area of the cap strip carrying a lubricant charge. Also, the forms of apparatus, as heretofore described, have particularly mentioned the fact that the lubricant is carried by the cap strip. While this is a preferred form and embodiment of the apparatus, since it does not require any changes in structure of the cap pistols either now existing on the market or to be hereafter constructed, yet the same advantages of lubrication can be obtained if an independent lubricant coated strip is passed through the pistol with the cap strip in a manner that the hammer of the pistol strikes the lubricant strip substantially simultaneously with detonation of an explosive charge. Such a form of apparatus is disclosed in Figure 16 wherein the cap roll 30 is arranged to pass through the pistol firing chamber and under the hammer 21a in the conventional manner. 30 In this arrangement, however, a separate lubricant strip 65 is positioned within the firing chamber 12a of the pistol. The lubricant strip 65 may also be provided in the manner of a roll similar to the cap strip 30 and can be threaded through the pistol adjacent the cap strip 30 so that when the hammer 21a is caused to strike a firing blow, the hammer will strike the lubricant strip 65 as well as the cap strip 30. By such an arrangement the lubricant upon the lubricant strip 65 is dispersed within the firing chamber 12a both by action of the hammer 21a and by detonation of the explosive charge.

In order to provide a method for easily treating cap rolls which are already in existence and a method which will alter to a minimum the process of manufacturing cap rolls to carry a lubricant, the apparatus disclosed in Figure 8 provides such means. In the disclosure of Figure 8 the cap rolls 30 are manufactured in conventional manner wherein the explosive charges are positioned upon a strip of suitable material and rolled into a helical coil. A plurality of such rolls can be placed within a suitable container and tumbled in a lubricant to cause the lubricant to adhere to the surfaces of the cap rolls. If the lubricant is of an inorganic nature, and is finely powdered, the lubricant will find its way into the crevices between the various layers of the cap roll, whereas, if the lubricant is of an organic nature and thus of an oily base, the powder charges can be suitably protected to permit dispersion of such a lubricant upon the surfaces of the cap roll strip, or even permit the lubricant to be absorbed into the body of the cap roll.

While the form and embodiment herein disclosed constitute preferred forms for practicing the teachings of my invention, yet there are many other specific forms of manufacture of cap rolls which will perform the same function, all of which are included within the scope of my invention.

Having thus fully described my invention,

what I claim as new and desire to secure by Letters Patent is:

1. A method for lubricating a toy cap pistol comprising, the step (a) of simultaneously advancing a cap strip and a lubricant carrying strip through a pistol, and the step (b) of simultaneously detonating a cap charge within the pistol and dispersing the lubricant from the lubricant strip within the interior of the pistol by the detonation of the cap charge.

2. In combination, a toy cap pistol having a hammer for detonating explosive charges, a cap strip having a plurality of powder charges thereon, and a strip carrying lubricant carried adjacent said cap strip, said hammer being adapted to explode said cap charge upon operation of said hammer to disperse said lubricant to the moving parts of the pistol simultaneously with explosion of said cap charge.

3. A device for providing lubrication for a toy cap pistol comprising a sheet-like body having one or more explosive charges thereon; and a lubricant in a charge and adapted to be scattered upon detonation of the charge.

4. A device for providing lubrication for a toy cap pistol comprising a sheet-like body having a succession of explosive charges thereon enclosed by said body, and a lubricating substance adjacent at least some of the charges and enclosed by said body and adapted to be dispersed from within said body upon detonation of the said charges.
5. A device for providing lubrication for a toy cap pistol comprising a sheet-like body enclosing a body of an organic lubricating material and one or more explosive charges for dispersing the lubricant from within the sheet-like body upon detonation of the charge.
- 15 6. A device for providing lubrication for a toy cap pistol comprising a sheet-like body enclosing a body of an inorganic lubricating material and one or more explosive charges for dispersing the lubricant from within the sheet-like body upon detonation of the charge.

ROBERT J. RICKENBACHER.
